ABSTRACT

A dry shaver having a plurality of shearheads one of them moving with its cutting surface sideways through friction with the skin.

FIG. I

FIG.2

FIG. 3

FIG. 5

FIG. 4

FIG. 6

INVENTOR
PAUL KOBLER

MECHANICAL RAZORS

BACKGROUND OF THE INVENTION

The present invention relates to electrical or mechanical dry shavers with a plurality of shearheads consisting of a case and inside a rotary motor or other driving means giving oscillating movements to the cutters inside the shearhead members. At least one shearhead where the cutting surface through friction with the skin is moved sideways the cutting surface or surfaces being lengthwise from end to end, whereby the angle between cutting surface of the shearhead and the skin of the face is changed, to a more acute angle, the skin entering then in a sharper angle into the slots of the cutting surface, whereby the skin in minute dimension is formed into a bulge, on said bulge the roots of the hair are more exposed to the cutting edges of the inner knife of the shearhead and a closer shave is achieved. In other words the penetration of the skin into the cutting slots of the shearhead is in minute measurement increased. Minute changes in the angle between skin and cutting surface of the razor have beneficial results.

Constructions with a lengthwise straight or curved shearhead have a great advantage compared with a circularly shaped shearhead. The natural way to shave is with back and forth movements. With such a natural way to shave, the result of the lengthwise shaped shearhead is much greater than with a circularly shaped shearhead. With a circularly shaped shearhead only a small advance section that touches the skin in forward and back strokes gives the same result, and it is the advance section in this invention that counts. With a lengthwise shaped shearhead the whole length of the shearhead advances simultaneously, that is the advance section where the invention takes place is multiplied by the many slots on a lengthwise shaped shearhead. It has to be considered that with a circularly shaped shearhead only one slot the most advanced one is in a perfect position to give the perfect result claimed by this invention.

Another object and advantage of this invention is, that it lends itself very easily to a balancing movement of the whole shaver. If 4 fingers are held above the shaver case and the thumb underneath the shaver case, the four fingers can balance the case back and forth over the thumb. With it the shearheads are balanced also which increases the efficiency of the present invention.

The inner cutter of the shearhead is reciprocated by a pin 27. This driving pin is solidly attached to oscillating lever 31. The driving pin 27 has over it a sleeve 28. Said pin sleeve 28 has at its base a shoulder. Spring 30 between said shoulder and the oscillating lever 31 presses the pin sleeve 28 into a small opening at the base of the inner knife and with it the inner knife is pressed into close contact with the cutting surface of the outer shearhead member. Not seen in the drawing is a cam mounted on the motor shaft. Said cam gives the oscillating motion to lever 31.

Another object of the invention is that the turning point for the sideways free movement of at least one shearhead on the shaver, may be varied. The turning point may be near or at the base or below the base of the shearhead. Another advantage of this invention is that with shearheads where the cutting surface consists of a sieve with holes even a small sideways yielding of the shearhead causes less pull on the stubble which have to be cut off.

Other objects and advantages of the invention will become apparent from the description now to follow of preferred embodiments thereof, in which reference will be had to the accompanying drawings in which:

FIG. 1 is a front view of a shearhead with lengthwise cutting surface, said shearhead attached to the casing that it will move sideways by friction with the skin of the face.

FIG. 2 is a different embodiment where the sideways turning mechanism of the shearhead is not in the center but off center.

FIG. 3 is a front view of a shearhead with the turning point for sideways movement of said head, at the base of the shearhead.

FIG. 4 is an enlarged section in a side view of a section of FIG. 1.

FIG. 5 is an assembly of three shearheads on a shaver case showing two of these heads movable sideways.

FIG. 6 is a part of the mechanism on which the shearheads seen in FIG. 1, 2 and 4 can move sideways through the friction with the skin.

In FIG. 1 a shearhead 1 is shown attached to a shaver case 2; to the shearhead are attached solidly two pins 3 and 4. In FIG. 10 we see further that pin 4 carries in a groove perforated plate 5. Groove 6 with this perforated plate 5 and also be seen in FIG. 2 and 4. Pin 4 is held in a tube 7. The double circles in FIG. 1 show cross sections of tube 7. As the shearhead needs very little sideways displacement to achieve the desired result in this invention the tubes 7 are made wider in diameter than the diameter of pins 3 and 4. 8 denotes the turning point of pin 4 which is also seen in FIG. 2. FIG. 1, 9 is a spring to hold pin 4 with the perforated plate 5 in tube 7. By pressing spring 9 towards tube 7 the pin 4 is released and the shearhead with the pins attached can be taken off the shaver.

In FIG. 2 a lengthwise curved shearhead is shown with a pin in an out of center attached tubing. The shearhead pin is held in that tubing 10 by a perforated plate 5. Tubing 10 has at its bottom the round shape 7 while its top has the oval shape 7a. Therefore pin 4 has a little play inside the tubing 7 as tubing 7 goes conically somewhat apart towards the top where it touches "1a". The conical structure of tubing 7 allows shearhead "1a" to be moved sideways by friction with the skin.

Tubing 7 and pin 4 are not on the center line of the shearhead and therefore the shearhead comb 11 will move at a further distances compared with shearhead comb 12. A sideview of FIG. 4 shows an enlarged shearhead 1b, with an enlarged pin 4b. Shown is also the perforated plate 5 with its swivel point 8 both located in the groove 6 of pin 4b.

The lower part 13 of pin 4 is in conical shape.

The conical shaped end of pin 4 allows the shearhead to be moved a small distance towards the tube walls, in each direction by friction with the skin. Perforated plate 5 has its turning point in the middle of plate 5 as also seen in FIG. 6d. with number 8.

FIG. 5 shows the lower end of tube 7 with slots 7s. Perforated plate 5 can be horizontally, sideways moved in these slots 7s. In FIG. 1 we see spring 9 with which the perforated plate 5 can be displaced. Said perforated plate 5 is seen in FIG. 1, 2, 4 and 5 and has a fulcrum 8, also seen in FIG. 1, 2 and 5, capable of letting pin 4 move sideways on it without friction. Pin 4 is seen in FIG. 1, 2 and marked 4b in FIG. 5.

It should be noted that the lower the fulcrum is located, the less the sides of the shearheads dip down with their sideways motions. Therefore a fulcrum placed at the middle height of the shearhead, or above it, dips circularly the sides of the heads too suddenly steep down and with it diminishes considerably the effect of this invention.

In FIG. 5 we see mounted on a shaver casing three shearheads No. 17, 18 and 19. The middle shearhead No. 18 is solidly mounted, or may be removed similar to the head shown in FIG. 1 with two pins like the pin on the left side of FIG. 1. However heads 17 and 19 move with the friction of the skin sideways in the same direction, opposite the direction in which the shaver is moved by hand over the skin of the face. The beneficial action of this sideways movement of the shearhead is increased if more heads may move sideways. The sideways curved motion with which the shaver is moved over the skin is indicated by arrow 20. We recommend to move the shaver over the skin for the first cut in straight movements back and forth like erasing a pencil mark. Then for the last cut a sideways curved motion is the best to get a close shave faster.

FIG. 6 shows two embodiments of perforated plate 5. No. 5a is a top view; of said plate and 5b a side view; the raised turning points 8 are indicated with number 8. Plate 5d with side view c has the turning point 8 in the middle of said perforated plate 5. The cutting surfaces of each shearhead seen in FIG. 1, 2, 3 and 4 are standing in an angle towards each other. However they may also be horizontal and have instead of cutting bars a sieve with holes.

In operation the advancing shearhead causes the skin to bulge before the cutting surface. The friction of the skin is bending the loosely mounted shearhead slightly backwards whereby the angle with which the skin enters into the cutting surface is changed to an acute angle resulting in a closer, faster more agreeable shave. As the loosely mounted shearhead is yielding to the motion of the shaver, the stubble move slower without pull between the cutting edges of the shearhead.

I claim:

1. A dry shaver having a plurality of shearheads with cutting surfaces, at least one of said shearheads loosely mounted on the head assembly, with the fulcrum below the middle of the height of said head, in order to achieve short, only little curved backward and forward side motions of the advancing edge of the cutting surface, said advancing edge moving in an almost flat curve which goes along considerably nearer a horizontal than a vertical imaginary line, said horizontal line going above the advancing edge of the shearhead, these motions caused by light friction on the skin, when the shaver is moved by hand over said skin, said short, free, without restraint lengthwise side motions of one or more shearheads moving always for-

ward and backwards in the opposite direction with which the shaver is moved over the skin, and exposed with the edge of its cutting surface to a bulge on the skin created by said advancing edge when the shaver is moved over the skin to be shaved, which results in a closer shave, the head is provided with a cooperating reciprocating inner cutter.

2. As described in claim 1 and provided with means limiting the extent of said short, almost flat curved side motions.

3. As described in claim 1, the fulcrum connected with a release mechanism that is holding and releasing the shearheads on the shaver case.

4. As described in claim 1: the loosely mounted shearhead being attached off center at the base of said shearhead, whereby one lengthwise edge of the shearhead base lifts itself with the friction of the skin higher up than the opposite lengthwise edge of said base, the loosely mounted shearhead moving more sideways on one side than on the other side, that is it moves more with the forward motion of the shaver case than with the backward motion of said case.

5. As described in claim 1, the cutting surfaces of said shearheads may be lengthwise curved and crosswise roof shaped.
